ROTARY FLUID MOTOR FOR DRY SHAVERS

Lester C. Merriman, Whitehorse, Yukon
Territory, Canada

Application February 6, 1948, Serial No. 6,792

3 Claims. (Cl. 253—2)

1

This invention relates to improvements in motor-driven dry shavers and the like, and more particularly to a pneumatically-operated device of this kind which is powered by the breath of the user, the primary object of the invention being to provide a dry shaver or the like which does not depend for its operation upon availability of electric current supply or sources of pressurized air or water.

Another important object of the invention is to provide a dry shaver or the like which is simple in construction and has fewer wearing parts and hence longer than usual life, and which can be operated more easily and at a lower cost than other powered devices of this kind.

Other important objects and advantageous features of the invention will be apparent from the following description and accompanying drawings, wherein merely for purposes of disclosure herein, a specific embodiment of the invention is set forth in detail.

In the drawing:

Figure 1 is a sectional plan view taken substantially on the center line through the shaver of the present invention, with parts of the casing broken away.

Figure 2 is a longitudinal sectional view taken on the line 2—2 of Figure 1.

Figure 3 is a transverse sectional view taken on the line 3—3 of Figure 2.

Figure 4 is a fragmentary transverse section taken on line 4—4 of Figure 2.

Referring to the drawings in detail, the illustrated dry shaver, generally designated 5, comprises a substantially-cylindrical elongated casing 6 rounded at its rearward end at 7 and indented on its underside at 8 and having a longitudinal semi-cylindrical enlargement 8' along one side. The forward end of the casing is externally reduced at 9 to telescope into an internally-reduced portion 10 on the rear end of a suitable form of cutter head 11, comprising, in this instance, the rounded shell 12 having the rectangular transversely-elongated portion 13 containing the stationary blades 14, with a movable blade assembly 15 positioned cooperatively behind the stationary blades for movement relative thereto. Screws 10' hold the head in place on the casing.

The casing 6 further comprises the intermediate partitions 16 and 17, respectively, which with the sidewall 18 of the casing define the rotor chamber 19, the partitions being formed with bearing apertures in which are journaled enlarged anti-friction bearings 20 and 21, respectively, on

2

the rotor shaft 22 at opposite ends of the closed hollow cylindrical turbine rotor 23. The rotor has longitudinally-extending blades or vanes 24 which curve in the circumferential direction opposite to the intended direction of rotation of the rotor, as shown in Figure 3.

The rotor shaft extends forwardly through another partition 25 forwardly of which the shaft has a flywheel 26 having an eccentric pin 27 extending into and operatively engaging in a socket 28 provided in the movable blade assembly 15. The rotor shaft extends rearwardly beyond the partition 16, where the shaft has a larger diameter flywheel 31, with its rear end supported in an anti-friction bearing 32 on a rear partition 33.

The casing sidewall 18 is provided with an air outlet opening 34 from the rotor chamber 19 at the bottom of the casing 6, while the air for driving the rotor 23 is conducted by a conduit 35 having a portion 36 extending along the casing sidewall 18, as shown in Figure 1, from a double curved portion 36' passing rearwardly at the center of the rear end of the casing. The conduit portion 35 has longitudinally-spaced baffles 35' which curve toward the rotor for directing the air tangentially through a longitudinal opening 34' in the inward side of the conduit portion 36, against the rotor blades 24. The conduit portion 36 is located, as shown in Figure 4, in the longitudinal enlargement 8' along the side of the casing 6.

Supplying this conduit with air for driving the rotor 23 is a flexible breath tube 37, terminating in a removable mouthpiece 38. In operating the device, the operator places the mouthpiece in his mouth, and exerting lung pressure after partially filling the lungs, expels the air through the breath tube 37, whereby the rotor 23 is rotated. Once the rotor has started, the momentum of the flywheels keeps the rotor running with little extra breathing effort during the application of the shaving head to the surfaces to be clipped or shaved.

The rear and larger diameter flywheel projects through a slot 39 provided in the indented casing portion 8 so that it can be turned with a finger to start the rotor turning, as or before the breath is blown through the tube 37 for operating the device.

What is claimed is:

1. In a pneumatic motor adapted for operation by the breath of a user, an elongated closed end casing serving as a handle and comprising a rotor chamber having a cylindrical side wall and end

walls, said end walls being longitudinally spaced from the ends of said casing, a rotor in said chamber extending between said end walls having longitudinally elongated blades extending the length of the rotor having edges running close to the cylindrical side wall of said chamber, said rotor having shaft portions journaled in said end walls and extending axially beyond said end walls into the spaces between said end walls and the adjacent ends of the casing, a conduit within and extending along one side of said chamber and formed with a longitudinal opening in its inward side extending the length of said chamber between said end walls, the side wall of the casing being formed with a breath discharge opening circumferentially spaced from said conduit, said conduit having a closed end and an open end, a breath tube having an end connected to the open end of said conduit and another end adapted to be placed in the mouth of the user whereby the user's breath can be expelled through the tube to drive the rotor, said conduit having longitudinally spaced baffles therealong for directing the breath coming through the breath tube against the rotor vanes through said longitudinal conduit opening.

2. In a pneumatic motor adapted for operation by the breath of a user, an elongated closed end casing serving as a handle and comprising a rotor chamber having a cylindrical side wall and end walls, said end walls being longitudinally spaced from the ends of said casing, a rotor in said chamber extending between said end walls having longitudinally elongated blades extending the length of the rotor having edges running close to the cylindrical side wall of said chamber, said rotor having shaft portions journaled in said end walls and extending axially beyond said end walls into the spaces between said end walls and the adjacent ends of the casing, a conduit within and extending along one side of said chamber and formed with a longitudinal opening in its inward side extending the length of said chamber between said end walls, the sidewall of the casing being formed with a breath discharge opening circumferentially spaced from said conduit, said conduit having a closed end and an open end, a breath tube having an end connected to the open end of said conduit and another end adapted to be placed in the mouth of the user whereby the user's breath can be expelled through the tube to drive the rotor, said conduit having longitudinally spaced baffles therealong for directing the breath coming through the breath tube against the rotor vanes through said longitudinal con-

duit opening, at least one of said shaft portions having flywheel means thereon located in a space between a chamber end wall and the corresponding end of the casing.

- 5 3. In a pneumatic motor adapted for operation by the breath of a user, an elongated closed end casing serving as a handle and comprising a rotor chamber having a cylindrical side wall and end walls, said end walls being longitudinally spaced from the ends of said casing, a rotor in said chamber extending between said end walls having longitudinally elongated blades extending the length of the rotor having edges running close to the cylindrical side wall of said chamber, said 10 15 rotor having shaft portions journaled in said end walls and extending axially beyond said end walls into the spaces between said end walls and the adjacent ends of the casing, a conduit within and extending along one side of said chamber and formed with a longitudinal opening in its inward side extending the length of said chamber between said end walls, the side wall of the casing being formed with a breath discharge opening circumferentially spaced from said conduit, 20 25 said conduit having a closed end and an open end, a breath tube having an end connected to the open end of said conduit and another end adapted to be placed in the mouth of the user whereby the user's breath can be expelled through the tube to drive the rotor, said conduit having longitudinally spaced baffles therealong for directing the breath coming through the breath tube against the rotor vanes through said longitudinal conduit opening, at least one of said shaft portions having flywheel means thereon located in a space between a chamber end wall and the corresponding end of the casing, and means on the other shaft portion adapting it for operative connection to utilization means.
